DISPENSING APPARATUS

Filed May 23, 1923

Inventor

Joseph La Reddola,

By his Attorneys
Redding, Greely, O'Shea & Campbell

UNITED STATES PATENT OFFICE

JOSEPH LA REDDOLA, OF BROOKLYN, NEW YORK

DISPENSING APPARATUS

Application filed May 23, 1928. Serial No. 279,865.

This invention relates to dispensing apparatus of the type adapted for dispensing measured quantities of a cream, such as shaving cream, tooth paste, etc. Existing forms of these devices have included receptacles for holding the tube and, in some instances, devices for ejecting measured quantities of the contents thereof, but none has combined a practical and effective tube holder which exerts sufficient squeezing pressure upon the tube with an effective means for dispensing the contents of the tube.

An object of the present invention is to provide an apparatus of the above character which combines a manual take-up or tension device with a spring tensioning device to exert a sufficient squeezing pressure upon the tube and a plunger operated mouth piece for the tube which ejects a given quantity of the cream when the plunger is depressed. The ejector is slidably carried in the fixture and, as the contents of the tube are consumed and the tube is rolled at its end, the ejector follows the tube into the position representing the condition thereof as being empty.

A further object of the invention is to provide a receptacle and apparatus which is simple in construction, easy to operate and the elements of which do not become damaged or get out of repair. Further objects will appear as the description of the invention proceeds and reference will now be had to the accompanying drawings, wherein:

Figure 1 is a view in side elevation showing a preferred form of the invention.

Figure 2 is a view in front elevation of the device shown in Figure 1.

Figure 3 is a view in section, taken on line 3-3 of Figure 2, and looking in the direction of the arrows.

Figure 4 is a view in section, taken on line 4-4 of Figure 1, and looking in the direction of the arrows.

Referring to the above drawings, reference character *a* designates a standard having a base *a'* which may be secured upon any desirable surface by means of screws *a''*. Along one side of the standard, a dove-tailed slot *a³* is formed and the upper extremity of the standard is bifurcated to provide two arms

a⁴. These arms have rollers *a⁵* mounted between their ends and are formed with downwardly extending shoulders *a⁶*. Extending upwardly from the faces of the shoulders *a⁶*, are guide rods *a⁷* upon which slides a cross-piece *b*. Coil springs *b'*, seated in recesses *b²* of the cross pieces *b* normally force the latter upwardly and tension the tube in a manner described hereinafter. Threaded recesses *a⁸* are formed in the shoulders *a⁶* and adjustable thumb screws *a⁹* vary the tension in the springs *b'*. Mounted between the cross-pieces *b* is a key *b³* which is slotted to receive the end of a tube *c* of any desired substance. It will be seen that the key *b³* may be turned to set up a desired tension in the tube and thus force the contents thereof downwardly through the mouth *c'* thereof.

As a dispensing, or ejecting means, a tube *d* is formed with a threaded neck *d'* for engaging the mouth *c'* of the tube *c*. This tube *d* is carried in a block *e* having a dove-tail *e'* for engaging the dove-tail slot *a³* in the standard *a*. In this manner, the ejector tube *d* follows the tube *c* upwardly as the contents

of the latter are dispensed. Below the neck *d'* an aperture *d²* is formed in the tube *d*. An inwardly extending portion *e²* provides a guide for a cylindrical plunger *f* which engages the inner periphery of the tube *d*. This plunger is provided with staggered apertures *f'* and *f²*, the former being aligned with the neck *d'* when the plunger is in its outer position, and the latter being aligned with the aperture *d²* when the plunger is pushed inwardly. A cap *f³* conceals the head of a screw *g* which extends through the plunger and is secured in the extension *e²*. A coil spring *g'* lies about the screw *g* and engages plunger *f⁴* in the plunger *f* to cause the latter

to normally lie in the position shown in Figure 3. About the coil spring, and closely fitting the restricted portion *g²* of plunger *f*, is a tube *g³* which protects the spring from the substance carried by the tube and serves to maintain a free action of the mechanism.

It will be seen that the space between the tube *g³* and the cylindrical plunger *f* will be filled with the substance carried by the tube *c* by reason of the pressure exerted upon the

upper end of the tube as described above. When the plunger f is depressed, aperture f' moves to the left and causes the substance within the plunger to be trapped. Simultaneously with this, aperture f^2 aligns itself with aperture d^2 and permits the contents of the plunger to be ejected.

It will be apparent that changes in the design and arrangement of parts may be made 10 without departing from the scope of this invention and the latter is not to be limited, save as defined in the appended claims.

I claim as my invention:

1. In a dispensing apparatus for a tube of 15 a fluid substance, a support, a key carried by the support for winding the end of the tube manually, squeezer rolls, means to mount the tube between the rolls, shoulders on the support, springs carried by the shoulders, and 20 blocks carried by the key against which the springs engage.

2. In a dispensing apparatus for a tube of 25 a fluid substance, a support, a key carried by the support for winding the end of the tube manually, squeezer rolls, means for exerting a pressure on the key, a casing carried by the tube, means to mount the casing slidably in the support, a plunger in the casing, and a spring for normally retracting the plunger.

3. In a dispensing apparatus for a tube of 30 a fluid substance, a support, a key carried by the support for winding the end of the tube manually, squeezer rolls, means for exerting a pressure on the key, a casing carried by the 35 tube, means to mount the casing slidably in the support, a hollow plunger in the casing, apertures in the casing and plunger, and a spring for normally retracting the plunger.

This specification signed this 22nd day of 40 May, A. D. 1928.

JOSEPH LA REDDOLA.
